W. DUCHEMIN.

Sewing Machine for Sewing Turned Shoes.

No. 91,101.

Patented June 8, 1869.

UNITED STATES PATENT OFFICE.

WILLIAM DUCHEMIN, OF BOSTON, MASSACHUSETTS, ASSIGNOR TO GEORGE B. BIGELOW, TRUSTEE, OF SAME PLACE.

IMPROVEMENT IN SEWING-MACHINE FOR SEWING TURNED SHOES.

Specification forming part of Letters Patent No. 91,101, dated June 8, 1869.

To all whom it may concern:

Be it known that I, WILLIAM DUCHEMIN, of Boston, in the county of Suffolk and State of Massachusetts, have invented an Improved Machine for Sewing Turned Shoes; and I do hereby declare that the following is so full and exact description thereof as to enable others skilled in the art to make and use my invention, reference being had to the accompanying drawings and to the letters of reference marked thereon.

To assist the mind in following the description of this machine the same letter, with a number annexed, is used for all parts of the device that act directly together to produce a desired result.

Drawings.

Figure 1 is a perspective view. Fig. 2 is a front elevation, showing the principal working parts of the machine. Fig. 3 is a cross vertical section of the same. Fig. 4 shows the position of the needle and needle-guard while passing through the shoe. Fig. 5 is a section of the "fingers" as they appear when open to clasp the thread. Fig. 6 shows the fingers in section, closed, giving the thread a quarter-turn. Fig. 7 shows the loop formed by the withdrawal of the thread-carrier, the fingers shown in section, as before.

E in all the drawings is the propelling-shaft for the whole machine, and has attached to it the cam-wheels E² E³ E⁴ E⁵. N, Figs. 2 and 3, is the fixed point or gauge, which serves as a guide, against which the workman holds the shoe while it is being sewed. F² F³ is the pressure-bar, F⁴ being the pressure-foot, whose function is to press down on the shoe and hold it firmly while the stitch is being formed. This pressure-bar is operated as follows: A spiral spring located immediately behind F², not shown in the drawings, serves to throw it up, while the cam-rod F, acting through the lever F¹, moves the pressure-bar down. This cam-rod F has a roller, F¹⁰, which is acted upon by the periphery of the cam-wheel E⁴, and is pressed down and so held, excepting the time that the depression f f, Figs. 2 and 3, in the periphery of E⁴, is immediately over it. At such time the spiral spring spoken of above is free to lift up the pressure-bar F², and thus

free the work for the action of the feed. At the same time that the pressure-foot relieves the work the cam Q⁷, on E⁴, operating through the lever Q⁶ and link Q⁴, Fig. 3, and the bent lever Q² Q³, Fig. 1, releases the standard P⁴ by withdrawing the wedge Q¹, thus allowing the arm P, which is supported by the standard P⁴, to be depressed sufficiently to allow the workman to turn the shoe. The feed-lever G, swinging upon the pivot G¹ and operated by the peripheral cam-slot between the cam-wheels E² E³, actuates the feed-point G² G³. The feed-point G² G³ swings on a pivot, G⁶, said pivot being free to slide in the plate C. G⁴ G⁴ are guides fastened to the plate C, which serve to limit the tipping-motion of the feed-point G² G³. Thus, as the point is pushed forward its rear end will swing upward toward the upper guide G⁴, while its forward or working end will be sufficiently depressed to impinge against the article to be fed forward; but when the feed-point is thrown backward its working point is elevated so as to free itself from the stock and not carry it backward. The amount of motion given to the feed-point—in other words, the length of the stitch—is regulated by the slotted guide G⁵, Fig. 2, which is held in any desired position by the screw G⁷. The plates K¹ and J¹, Fig. 3, are connected to the face-plate C, and are provided with circular slots K² J². In the slot K² the needle-carrier K³ traverses, while in the slot J² the needle-guard carrier J³ traverses. This needle-carrier K³ is operated by the cam-rod K, while the needle-guard carrier J³ is operated by the cam-rod J, Fig. 2. The radial arm P and its adjuncts are peculiar in construction and operation. The arm P is attached to a segment, P¹. This segment is a part of a circle the center of which is near the upper end of the arm P, and is concentric with the curved surface of the upper end of the arm P, so that when P¹ slides in the grooves made in P² P³ the upper end of the arm P maintains its relative position in all respects with relation to the guide N—in other words, the upper end of the arm P is not moved out of position by any movement of the lower end so long as the segment P¹ is within the grooves in P² P³. By this arrangement any part of a shoe may be sewed. By raising the lower end of the arm

P the whole arm will assume nearly a horizontal position, and will extend to the extreme tip or toe of a shoe. By bringing the arm to nearly a vertical position the heel of the shoe may be sewed. The thread-carrier L⁵ is connected to the curved slide L³, which is operated by the cam-rod L acting through the lever L¹ on the back of the plate C, shown in Fig. 2 by dotted lines. The fingers F⁴ F⁵, Figs. 2 and 3, are peculiar in shape and action, and serve to seize one of the threads and place it in the proper position for forming the loop. They are operated as follows: They close by passing each other edgewise and in line with the center joint of the said fingers. When the jaws are opened, for the purpose of seizing the thread brought forward by the thread-carrier L⁵ for forming the loop, they assume the position shown in Fig. 5. When closed, with the thread between them, they are as represented in Fig. 6; and when the thread-carrier has receded the loop is fully made, as is shown in Fig. 7, said loop being at right angles with the loop when it is first brought forward by the thread-carrier L⁵, and between the needle K⁵ and the feed G², having received in its formation a full quarter-turn for that purpose. When the fingers are thrown back, as will be hereafter described, the loop will be between the thread-carrier L⁵ and the needle K⁵, and in such a position that the thread-carrier must pass through this loop, formed by its own thread, before passing under the thread brought forward by the needle K⁵. The spring F¹¹, Fig. 3, serves to keep the fingers closed, unless they are opened, as they are at the proper time, by the action of the lever H H¹, through the lever H². The side cam E⁶ serves to move H. The lateral reciprocating motion of the fingers is caused by the link M⁵ working in conjunction with the spring F⁶. The link M⁵ is connected to the finger F⁴ by means of the screw F⁹, and motion is communicated to it by the bent lever M⁴, which is connected with the link M, which in turn is operated by the thread-carrier slide L³. The link M⁵ draws the upper end of the fingers F⁴ F⁵ over toward the left until the hook F¹², which is attached to F⁴, catches upon the pin F⁷. The fingers are held in this position until the arm F⁸, which is connected to the pressure-foot F², rises sufficiently to raise the hook F¹² off the pin F⁷. This releases the upper end of the fingers, and the spring F⁶ draws them over to the right, in the position shown in Fig. 2. J⁶, Figs. 2 and 3, is the needle-guard, circular in form, and round in section to within a quarter of an inch of the point, where it is concavo-convex in section. In forming the point, the upper or concave side must be exactly the reverse of the shape of the lower side of the needle K⁵, so that the guard may underlie the point of the needle in such a manner that the needle and needle-guard together will form, as it were, a continuous needle and move together through the same perforation, thus preventing the thin upper stock from being torn by catching on the point of the needle.

The method of operating my machine is as follows: Having threaded the needle K⁵ and thread-carrier L⁵, which is done by placing the thread through the eye of each from the under side, the operator places the shoe in such a manner between the arm P and the sewing-gauge N that the point of the gauge N shall be inside of and follow the channel cut for sewing on the sole. The sole is then pressed up against the sewing-gauge N by the spiral springs P⁶, and is kept firmly in its place, during the process of driving the needle and drawing the thread to form the stitch, by the wedge Q Q¹. When the shoe is thus secured, the pressure-bar F³, Fig. 2, is brought into position, and presses firmly the upper-leather of the shoe and keeps it in place while the stitch is being made. The needle-guard J⁶, by the action of the cam E⁶ on the rod J, is brought down just sufficient to pierce the upper-leather of the shoe. There it remains stationary until met by the point of the needle K⁵, when it assumes the position shown in Fig. 4. It now recedes as the needle advances, the point of the needle K⁵ being just above and touching the point of the needle-guard J⁶, which thus forms a guard, that the needle may not tear the thin upper-stock of the shoe. The needle, having come forward the full length of the stitch, is drawn back sufficiently to slack the thread enough to allow the thread-carrier L⁵ to pass between the needle K⁵ and its thread, said thread being upon the upper side of said needle, when the needle K⁵ remains stationary long enough to enable the thread-carrier L⁵ to perform its part of the work, which consists in bringing forward a second thread, that is caught and held in place by the fingers F⁵.

The fingers F⁴ and F⁵ act as follows: When the thread-carrier L⁵, being acted on by the cam E⁶, has brought forward the thread, the fingers being opened by the action of the cam-lever H², and moved forward by the mechanism M M² M³ M⁴ M⁵, comes in such a position as to catch the thread of the thread-carrier L⁵, then the pressure of the cam-lever H² is removed and the lower end of the fingers seize the thread. Now the thread-carrier L⁵ recedes, leaving the thread, which is thus made to form a loop at right angles with the loop of the needle K⁵. The needle K⁵ is then brought back to its original position, and a stitch is formed. The pressure-bar F³ is now relieved from the action of the cam E⁴, and, through the agency of a spring, not shown, it rises. In rising, a small bar, F⁸, touches the hook F¹², relieving the fingers from the position in which they were brought when they caught the thread of the carrier L⁵. Now, by the action of the spring F⁶, they are brought back to their original position, still retaining the loop in such a position that the thread-carrier L⁵ can pass through it, before passing the needle K⁵, in making the succeeding stitch. The wedge Q Q¹ is then drawn back, relieving P⁴ from its fixed position, so that the arm P may be depressed, and thus allow the shoe to be moved forward the

length of a stitch by the feed G². The lower end of the bar F² F³ is to be constructed in form the exact reverse, on its under side, of the upper surface of the tip of the arm P P¹. In practice this bar has a tooth inserted in its lower face for the purpose of preventing the upper stock from slipping while the stitch is being made.

In this application I do not particularly claim the supporting-arm P P¹, nor the reciprocating bar F² F³, they being claimed in an application filed by me January 23, 1869; but

What I do claim, having thus described my invention, and desire to secure by Letters Patent, is—

1. The needle-guard J⁶, constructed as described, in combination with the needle K⁵, when operating together, as described, and for the purpose set forth.

2. The wedge Q Q¹, in combination with the

standard P⁴ and the arm P P¹, arranged and working substantially as described, and for the purpose set forth.

3. The fingers F⁴ F⁵, or their equivalents, when operated substantially as described to seize the loop and give it a quarter-turn, substantially as described, and for the purpose set forth.

4. The thread-carrier L⁵, arranged and working, in combination with the fingers F⁴ and F⁵, substantially as described, and for the purpose set forth.

In testimony whereof I have signed my name to this specification in the presence of two subscribing witnesses.

WILLM. DUCHEMIN.
